CLAIM

The ornamental design for a dual puzzle-piece-shaped bottle for cosmetics as shown and described.

DESCRIPTION

FIG. 1 is a perspective view of a dual puzzle-piece-shaped bottle for cosmetics;

FIG. 2 is a right side elevational view of the dual puzzle-piece-shaped bottle for cosmetics;

FIG. 3 is a top plan view of the dual puzzle-piece-shaped bottle for cosmetics;

FIG. 4 is a bottom plan view of the dual puzzle-piece-shaped bottle for cosmetics;

FIG. 5 is a front elevational view of the dual puzzle-piece-shaped bottle for cosmetics;

FIG. 6 is a back elevational view of the dual puzzle-piece-shaped bottle for cosmetics; and,

FIG. 7 is a left side elevational view of the dual puzzle-piece-shaped bottle for cosmetics.

The logo is shown in broken lines and forms no part of the claimed design.
